MICRON CONTROL FOR AIR SEPARATORS

Charles Edward Hermann, St. Louis, Mo.

Application July 22, 1933, Serial No. 681,682

4 Claims. (Cl. 209—144)

This invention relates to new and useful improvements in air separators of the type disclosed in my copending application filed August 13, 1931, Serial No. 556,477.

In this type of separator the pulverized material is conveyed by currents of air from the grinder into the separator through a plurality of inlets formed in the circumferential wall of the separator near the top thereof. The separator is connected by a suitable pipe to an exhaust fan and the air currents utilized to convey the material to the separator are produced by suction created by said fan. The material upon entering the separator receives circular centrifugal motion which causes the coarse material to drop to the bottom of the separator while the fine material is conveyed out of the separator through the discharge pipe. This swirling motion is imparted to the air and to the material through the medium of vanes or deflector plates which are arranged adjacent to the inlets and extend inwardly therefrom into the separator and control the direction of flow of the air.

As is well known in the art, the finest screen that can be made is 400 mesh so that particles of material of 1/400 of an inch can be measured or passed by said screen. Particles smaller than this size are commonly measured by microns. A micron is 1/10000 of a centimeter or approximately 1/25400 of an inch. In order to obtain a knowledge of the average particle size of a pigment or similar material, it is customary to count the number of particles of different micron sizes when observed through a very powerful microscope and to obtain from them an average particle size.

In most cases the finer the average particle the more desirable it is for use as paint pigment because it will stay in suspension better and absorb more oil due to the increased total surface.

With an ordinary air separator a product may be ninety-nine percent (99%) through 300 mesh and yet have a comparatively coarse average particle size.

One object of the present invention is to provide a device of the class described whereby the average particle size of the ground product can be varied or controlled at a given vane setting. Other objects of the invention are to provide a ring which is movably mounted so as to adjust the area of the opening between the outer and the inner cone members, thereby regulating the flow of air therebetween.

Further objects of the invention are to pro-

vide simple means for actuating such ring and holding it in adjusted position.

Additional objects of the invention are to provide a simple micron control for air separators and classifying equipment which is of simple construction, can be easily operated and adjusted, and which insures the production of more finely ground material than produced heretofore.

With these and other objects in view, my invention consists in certain novel features of construction and arrangement of parts, hereinafter more fully described and claimed, and illustrated in the accompanying drawings, in which—

Figure 1 is a diagrammatic view showing the arrangement of the separator and the parts associated therewith.

Figure 2 is an enlarged vertical cross section, partly broken away, of the separator.

Figure 3 is a horizontal cross section taken on line 3—3 of Figure 2.

Figure 4 is an enlarged fragmental horizontal cross section.

Figure 5 is an enlarged vertical cross section taken on line 5—5 of Figure 3.

Figure 6 is a fragmental detail cross section of a modified form of my invention.

Figure 7 is a fragmental detail cross section showing the adjustable member movable downwardly.

Referring by numerals to the accompanying drawings, 10 indicates a separator, the lower end 11 of which is connected by a conduit 12 to a feeder 14. This feeder or source of supply of material may be of any desired construction. It may be, for instance, in the form of a mill wherein the material is reduced to suitable degrees of fineness before being admitted into the separator. Leading from the upper end of the separator is a conduit 15 which connects to the inlet of a suitable exhaust fan 16. This fan produces suction in the separator, thereby causing air to flow from the feeder through conduit 12 into said separator. In doing so, the air carries the pulverized material from the feeder to the separator and delivers it therein in a manner hereinafter more fully described, whereby the coarse particles are separated from the fine material. The coarse material is collected in the separator and the fine material passes through conduit 15 to the exhaust fan 16, thence through a conduit 17 to a cyclone collector 18. The material which is of suitable fineness is collected in this cyclone collector and can be discharged through the lower end 19 by opening a suitable gate 20. Preferably the air is returned from the cyclone collector 55

to the feeder through a conduit 21, thereby permitting recirculation of the air through the system. However, this air connection between the cyclone collector and the feeder may be dispensed with without interfering in any way with the operation of my separator. The cyclone collector may also be dispensed with or placed in a different position without interfering in any way with the operation of my separator.

10 Where air return conduit 24 is used, a dust collector 22 may be connected by a connection 24 to the return conduit 21, as indicated at 25. This dust collector may be of any well known construction, the type shown being of the tubular kind.

15 The object of this dust collector is to dispose of any excess air that may come into the system through the feeder or otherwise. The dust collects in the lower end of the dust collector and can be discharged therefrom by a suitable valve 20 arranged therein.

The separator 10 is in the form of an inverted cone and consists of an outer shell 26 and an inner shell 27. The inner shell is of smaller dimensions than the outer shell and is spaced 25 therefrom so as to provide an annular receiving chamber 28 to the lower end of which is connected the discharge end of conduit 12 so that the pulverized material is discharged into this chamber 28. The inner shell 27 forms a separating 30 chamber 29, the lower end of which terminates in a spout 30 which extends outwardly through shell 26 and is closed by a gate 31. Thus by opening 35 said gate the material collected in chamber 29 can be discharged through said spout.

35 The upper portion of outer shell 26 is formed cylindrical as indicated at 32 and the upper portion of the inner shell 27 is similarly shaped as indicated at 34. These cylindrical portions are 40 concentrically arranged to provide an annular chamber 35 which forms the upper end of the chamber 28.

The upper end of outer shell 26 is closed by a plate 36 which forms the top of the separator and is secured to the end of cylindrical portion 32 in 45 any suitable manner, such as an angle iron ring 37. This top plate is formed with a central opening in which is received the inlet end of the pipe connection 15.

The upper end of portion 34 of inner shell 50 member 27 terminates a suitable distance below plate 36 to provide a communicating opening between chambers 29 and 35. This circumferential opening is provided with a plurality of spaced-apart vertically disposed vanes 38 which divide 55 said opening into a plurality of inlets 39 through which the air carrying the pulverized material enters chamber 29 from chamber 35.

These vanes extend between the upper edge of cylindrical portion 34 and plate 36 and their outer 60 edges are disposed within the vertical plane of said cylindrical portion. The upper end of each vane is provided with an upwardly projecting trunnion 40 which is journaled in top plate 36 and extends thereabove. The lower end of each vane 65 is provided with a downwardly projecting trunnion 41 which is journaled in the horizontally disposed flange of an angle iron ring 42. This ring is secured to the inner side of a collar 44 which latter is secured to the inside of the upper edge of 70 cylindrical portion 34. As shown, the upper edge of collar 44 projects a suitable distance above the lower ends of said vanes. Thus collar 44 not only forms reinforcement for the upper edge of inner shell 27 but also prevents leakage of air past the 75 lower ends of said vanes.

A ring 45 of angle iron is secured to the top plate 36 adjacent to and outwardly of the upper ends of vanes 38. The vertical flange of ring 45 extends downwardly and encircles said vanes and forms a seal to prevent leakage of air past the 5 upper ends of said vanes.

The vanes are set tangentially to the axis of chamber 29 so that the air and the ground material carried thereby, upon entering said chamber, receive whirling motion. The centrifugal 10 force causes the coarse particles of material to be separated from the air and from the finer particles and to be collected in the lower end of the separating chamber 29 while the air and fine material is discharged from the chamber through 15 pipe connection 15.

Vanes 38 are arranged comparatively close together and they are comparatively deep or of substantial widths so that each inlet 39 formed by the vanes is narrow and deep. This serves to 20 direct the currents of air in proper direction and impart thereto the desired whirling motion and prevents the formation of stray currents which would impair the efficiency of the separator.

The cylindrical portions 32 and 34 of shells 26 25 and 27, respectively, are secured together in spaced-apart relationship by means of a plurality of spacers 46 arranged equidistant about the axis of the separator. Each spacer is substantially of U-shape and the shorter or inner arm 46a is 30 secured to the outer face of the cylindrical portion 34 and to collar 44. The longer or outer arm 46b is secured to the inner face of cylindrical portion 32 and to ring 37. The end 46c of each arm 46b is preferably bent inwardly in a horizontal plane and extends under and is secured to the underside of plate 36.

Preferably the vanes 38 are mounted so that the tangential angle thereof can be varied as desired. The upper trunnions 40 which project 40 outwardly about plate 36 have each secured thereto an arm 47. Each arm is slotted in its end and engaging said slot is a vertically disposed pin 48 fixed to and depending from a horizontally disposed ring 49. The latter is movably mounted 45 on plate 36 by means of rollers 50. This ring is movable concentrically of the axis of the separator in either direction for simultaneously operating all of said arms so that vanes 38 can be adjusted relatively to the axis of the separator so as 50 to vary their tangential angles and increase or decrease the whirling motion of the air and the pulverized material carried thereby. The rollers 50 are mounted in brackets 51 which latter are secured to plate 36. The adjusting ring 49 can 55 be operated in any suitable manner.

In order to insure production of pulverized material which can be measured in microns, I provide a movable means or collar 52 which can be raised or adjusted so as to reduce the opening between chambers 28 and 29. This results in greater velocity of the flow of air and pulverized material carried thereby into separating chamber 29, thereby increasing the centrifugal action so that a larger amount of comparatively coarse 65 material is deflected downwardly in said chamber and only very fine material is discharged through the pipe 15.

This collar 52 is arranged externally of the cylindrical portion 34 and is of substantially the 70 same height so that when said collar occupies lowered position (see Fig. 2) its upper end is substantially flush with the upper end of said cylindrical portion.

As the arms 46a of spacers 46 are secured to 75

the outer face of the cylindrical portion 34 and the adjustable ring or collar 52 encircles said arms 46a, the spacers thus formed between said arms are preferably filled with segmental sections or fillers 54 which are of the same thickness as said arms and are secured to the cylindrical portion 34. Thus said adjusting collar is in air tight engagement with said cylindrical portion and no leakage of air between said collar and said 10 cylindrical portion can take place.

The collar is supported in position by a plurality of rods 55 which extend downwardly through apertures formed in top plate 36 and have their lower ends secured to said collar, as indicated at 56. These rods are spaced equidistant about the axis of the separator. Each rod is provided with a plurality of spaced-apart horizontally disposed apertures 57. A pin 58 is adapted to be inserted in any one of the apertures of each rod and is adapted to bear against the upper face of plate 36, thereby limiting the downward movement of said rod and supporting collar 52 in position within the separator. To raise the collar 52, each rod 55 is pulled, permitting the distance of one or more apertures as the case may be, whereupon pin 58 is inserted into the aperture nearest plate 36. To lower the collar, pin 58 is withdrawn from the particular aperture of each rod and is inserted in the next higher aperture, thereby permitting said collar to drop the required distance. The collar 52 can be supported in its lowered position by the horizontal portions 46d of spacers 46. The collar 52 can be easily operated, increases the efficiency of the separator, and enables the production of finer average particle size pulverized material.

The use of rings 44 and 45 prevents leakage of air past the ends of vanes 39 and the consequent impairment of the efficiency of the separator. 40 The air and pulverized material carried thereby can enter the separating chamber 29 only through the inlets 39 and the vanes 38 impart to the air the required tangential angle, or whirling motion.

45 The centrifugal action produced by this motion causes the comparatively coarse particles of material to be moved against the wall of the outer shell or cone member 27 and then to drop into the lower end of said member. The fine 50 particles remain in suspension in the air and are carried thereby away from the separator to discharge pipe 45.

As the collar 52 is raised, the cross sectional area of each inlet is correspondingly reduced, 55 thereby increasing the velocity of air entering the inner or separating chamber 29 and increasing the centrifugal action so that a finer separation of the ground material takes place.

In the modified form shown in Figure 6, the 60 collar 52 is adjustable by means extending downwardly and outwardly through the side wall of the outer member 26. This means consists of screw-threaded rods 59 which are secured at their upper ends to the ring or collar 52, as indicated at 60, and which rods extend downwardly and outwardly through member 26 and through bearing 61 fixed thereto. A nut 62 is revolvably arranged between abutment members 63 and 64 of each bearing 61 and receives the corresponding screw 59. Thus by turning nuts 62, rods or screws 59 are raised or lowered accordingly, thereby adjusting collar 52 and regulating the size of inlets 39.

In the modified form shown in Figure 7, an 75 adjustable collar or band 65 is shown normally

occupying position above inlets 66 and movable downwardly to reduce the vertical dimension thereof. This band is operable by means of rods 67 which are similar to rods 55 of the preferred form. The inlets 66 are formed in the cylindrical portion 34a of inner cone 27a and the upper end of said portion 34a extends to top wall 36a, while the vanes 38a are spaced therefrom. The upper trunnion 40a of the vanes are lengthened and project upwardly through top 36a.

The provision of a ring or collar between the separating chamber or inner cone member and the annular chamber or the outer cone member, restricting the inlet connections between said chambers, insures a finer separation of the pulverized material. By making the ring adjustable the areas of said inlets can be regulated to obtain pulverized material of a finer average particle size.

Where the ring is used in combination with the vanes, the adjustments of the latter and of the ring can be made independently of each other.

I claim:

1. In a separator of the class described, the combination of an outer inverted cone member having its lower end forming an inlet, a top wall for closing the upper end of said cone member, an inner inverted cone member arranged within and spaced from said outer member and having its lower end forming an outlet for coarse material, an open-ended cylindrical portion arranged on the upper end of said inner member and terminating short of said top wall, a plurality of vertical, non-radial vanes arranged peripherally between the upper end of said cylindrical portion and said top wall, said vanes all forming substantially equal angles with the radii through their respective points of intersection with said cylindrical portion, said vanes being disposed within the vertical plane of said cylindrical portion and forming a plurality of inlets, a pipe extending downwardly and axially through said top wall into said inner cone member and forming an outlet for air and fine material, and a collar slidably mounted exteriorly on said cylindrical portion and movable upwardly to reduce the effective area of said inlets.

2. In a separator of the class described, the combination of an outer inverted cone member having its lower end forming an inlet, a top wall for closing the upper end of said cone member, an inner inverted cone member arranged within and spaced from said outer member and having its lower end forming an outlet for coarse material, an open-ended cylindrical portion fixed to the upper end of said inner member and terminating short of said top wall, a plurality of vertical, non-radial vanes arranged peripherally between the upper end of said cylindrical portion and said top wall, said vanes all forming substantially equal angles with the radii through their respective points of intersection with said cylindrical portion, said vanes being disposed within the vertical plane of said cylindrical portion and forming a plurality of inlets, a pipe extending downwardly and axially through said top wall into said inner cone member and forming an outlet for air and fine material, a collar slidably and exteriorly mounted on said cylindrical portion and movable upwardly to reduce the effective area of said inlets, and means located exteriorly of said outer cone member for adjusting said collar.

3. In a separator of the class described, the combination of an outer inverted cone member

having an inlet, a top wall for closing the upper end of said cone member, an inner inverted cone member arranged within and spaced from said outer member and having its lower end forming an outlet for coarse material, a cylindrical extension fixed on the upper end of said inner member and terminating short of said top wall to form an inlet opening between the upper ends of said cone member, a plurality of vertical, non-radial vanes arranged peripherally between the upper end of said cylindrical portion and said top wall, said vanes all forming substantially equal angles with the radii through their respective points of intersection with said cylindrical portion, said vanes being disposed wholly within the vertical plane of said cylindrical extension and forming a plurality of inlets, said vanes being adjustable to regulate the angle of inclination of each inlet, a pipe extending downwardly and axially through said top wall into said inner cone member and forming an outlet for air and fine material, a collar slidably and exteriorly mounted on said cylindrical extension and movable axially thereof to reduce said inlet opening between the upper ends of said cone members and reduce accordingly the effective area of said inlets.

4. In a separator of the class described, the

combination of an outer inverted cone member having its lower end forming an inlet, a top wall for closing the upper end of said outer cone member, an inner inverted cone member supported within said outer cone member, a cylindrical extension fixed to the upper end of said inner cone member and terminating short of said top wall to form an inlet opening between said cones, a plurality of vertically disposed vanes arranged peripherally between the upper end of said cylindrical extension and said top wall, each vane being of substantially greater width than the distance between two adjacent vanes whereby the inlet passages formed thereby are comparatively narrow and deep to insure the discharge of air and material into said inner cone member in the desired direction, said vanes being adjustable to regulate the angle of inclination of each inlet, a pipe extending downwardly through said top wall into said inner cone member to form an outlet therefor for air and fine material, and a collar slidably and exteriorly mounted on said cylindrical extension and adjustable axially thereof to regulate the effective areas of the outer ends of said inlets.

CHARLES EDWARD HERMANN.
